LINK TYPE FLOOR MAT

Kenneth E. Brock, Toledo, Ohio, assignor to American Mat Corporation, Toledo, Ohio, a corporation of Ohio

Filed Aug. 26, 1960, Ser. No. 61,906

Term of patent 14 years

(Cl. D9—6)

FIG. 1 is a plan view of a link type floor mat broken away along the dotted lines to indicate indeterminate length and width and disclosing my new design.

FIG. 2 is a plan view of a single link of the type utilized in the mat of FIG. 1;

FIG. 3 is a front view in elevation of the link shown in FIG. 2;

FIG. 4 is an end view in elevation of the link shown in FIG. 2, and

FIG. 5 is a fragmentary vertical sectional view taken along the line 5—5 of FIG. 1 and shown on an enlarged scale.

I claim:

The ornamental design for a link type floor mat, as shown and described.
